TOOL FOR INSERTING INSULATOR SCREWS
Gordon C. Swenson, 310 Arbuckle Road, Erie, Pa.
Filed Oct. 25, 1961, Ser. No. 147,510
1 Claim. (Cl. 145—50)

This invention relates to tools for driving screws and, more particularly, to tools for driving screws into public utility poles, building walls, and the like for supporting electrical power line wires.

Tools for driving screws for supporting insulators have been made previously as shown in Patent Nos. 685,606 and 1,619,043. Also, tools for driving curved screws for supporting insulators have been made as shown in Patent No. 2,437,762. In order to drive each type of screw shown in the patents, a separate tool is required.

The present invention contemplates the use of a single tool for driving both types of screws shown in the first two mentioned patents so that a lineman need carry only a single tool in his truck in order to install either type of insulator.

It is, accordingly, an object of the present invention to provide an improved combination tool for driving a plurality of types of screws.

Another object of the invention is to provide an improved tool.

A further object of the invention is to provide a tool which is simple in construction, economical to manufacture, and simple and efficient to use.

With the above and other objects in view, the present invention consists of the combination and arrangement of parts hereinafter more fully described, illustrated in the accompanying drawings and more particularly pointed out in the appended claims, it being understood that changes may be made in the form, size, proportions, and minor details of construction without departing from the spirit or sacrificing any of the advantages of the invention.

In the drawing:

FIG. 1 is an isometric view of a tool according to the invention; and

FIG. 2 is a view similar to FIG. 1 of the other type of tool according to the invention.

FIG. 3 is a longitudinal cross sectional central view taken through FIG. 2.

Now with more particular reference to the drawing, 45 a tool 10 is intended to drive screws such as shown at 11 and to also drive screws such as screw 12; that is, either the screw 11 or the screw 12 can be driven by the tool 10. The tool is made up of a handle 14 which has a screw driver shaft 15 slidably and reciprocably received in a 50 central bore 26 therein.

The shaft 15 has a screw driver blade 16 on one end and on the other end a groove or bifurcated part 17 which, in practice, fits over the round side of a screw such as the screw 12. The intermediate part of the screw driver blade 55 16 is threaded and the threaded part engages a threaded bore in a handwheel 18. The handwheel 18 is disposed in a slot 29 which intersects the bore 26.

A slot 30 is formed on one side of the handle 14 and it extends around the end thereof opposite a cleft 20. 60 Therefore, the curved part of the body of the screw 12 rests on the bottom of this groove and is rigidly held for driving. The body has the generally T-shaped slot 65 therein which defines the cleft and this cleft receives a flange 22 on an insulator 19. The flange is received in the cleft as shown in the aforesaid patents. A bore 23 in the handle 14 intersects the bore 26.

2

When the handwheel 18 is rotated in one direction, the shaft 15 moves toward the cleft 20 to force the blade 16 into the slot in the screw 11 and therefore clamp the insulator 19 in the cleft 20 between ears 21 and the bottom of the cleft.

When the handwheel 18 is rotated in the other direction, the shaft 15 is moved toward the screw 12 so that the legs of the bifurcated part 17 are moved to receive the side of the screw and clamp it in the bore 23.

10 In operation, the screw 12 is put through the bore 23 in the handle and the handwheel rotated until the shaft 15 brings the bifurcated part 17 firmly around the screw 12. Then the operator can hold the handle 14 in his hand and strike the screw 12 attached to the handle against a building to start the screw 12. The operator 15 can then rotate the handle 14 to screw the screw 12 into the building.

In order to use the other type of screw 11, the device operates exactly as in the aforesaid patents.

20 The foregoing specification sets forth the invention in its preferred practical forms but the structure shown is capable of modification within a range of equivalents without departing from the invention which is to be understood is broadly novel as is commensurate with the appended claims.

The embodiments of the invention in which an exclusive property or privilege is claimed are defined as follows:

30 A screw driver mechanism for workpieces such as a curved insulator screw comprising
a handle,
a shaft threadably received and reciprocably movable
in a threaded bore in said handle,
35 a hole in said handle angularly disposed relative to
said shaft and intersecting said threaded bore for re-
ceiving the body of a workpiece,
a first slot in one side of said handle,
said first slot terminating at one end at the end of said
handle remote from said shaft,
said first slot terminating at its other end at said hole,
said shaft having a flat sided handwheel attached to it,
said shaft terminating adjacent said hole in a bifurcated
end defining a curved end surface,
and a second slot extending through said handle,
said handwheel being disposed in said second slot and
extending beyond the outside thereof,
said first slot being adapted to receive a curved work-
piece with a part of said workpiece extending through
said hole and said bifurcated end of said shaft in sur-
face contact with said workpiece whereby said work-
piece may be held in said hole.
